UNITED STATES PATENT OFFICE.

JEAN B. DAUDELIN AND EUSEBE H. DAUDELIN, OF FALL RIVER, MASSACHUSETTS.

SHUTTLE.

1,117,002.

Specification of Letters Patent. Patented Nov. 10, 1914.

Application filed May 12, 1913. Serial No. 766,962.

To all whom it may concern:

Be it known that we, JEAN B. DAUDELIN and EUSEBE H. DAUDELIN, citizens of the United States, residing at Fall River, county 5 of Bristol, and Commonwealth of Massachusetts, have invented certain new and useful Improvements in Shuttles, of which the following is a specification.

This invention relates to hand threading 10 shuttles and particularly to a guard for the threading eye of such a shuttle.

The dethreading tendency due to the writhing and twisting action of the thread during the run of the shuttle is well recognized in the art and it is the object of our present invention to provide simple and efficient means capable of application to any shuttle of ordinary type for overcoming this difficulty. Most of the thread guards here- 20 tofore devised have been expensive and such as have come into practical use have for the most part been of the bushing type. We have found that the bushing is unnecessary and in the form of our invention which has 25 proved best adapted to practical use we construct the guard of wire.

In the accompanying drawings we have shown our wire eye guard which consists of a bar through the eye, transverse of the 30 shuttle and above the entry of the threading passage to the eye and terminating in a spaced loop returned across itself and the threading slot, applied on the shuttle in its preferred form.

35 The invention will be more fully described in the specification which follows, throughout which and the drawings above referred to, like reference numerals are employed to indicate corresponding parts.

40 In the drawings, Figure 1 is a plan view of the threading end of the shuttle equipped with our invention, Fig. 2 is a longitudinal view, partly in section of the same, Fig. 3 is a view of the thread guard removed from 45 the shuttle and Fig. 4 is a side elevation of the threading end of the shuttle.

The shuttle body 1 may be of any construction having a bobbin chamber 2 in which is located a bobbin 3 on which is 50 wound a thread T.

From the forward end of the bobbin chamber 2 leads the eye 4 to which the threading slots 5 and 6 connect. The slot 5 is in the form shown diagonally disposed 55 with respect to the longitudinal axis of the shuttle and so sawed as to develop a curve

on the shuttle top. At one side of the opening between the eye 4 and the chamber 2 a pin 11 is usually driven for strengthening the tongue of wood formed in the shuttle body 1 by the two slots 5 and 6. This pin forms also a smooth guard and wear post over which the thread T runs when properly lodged in the eye 4. All this is usual and standard construction and only 60 necessarily considered in connection with the guard which we will now describe. This guard comprises a relatively straight shank 13 extending transversely of the shuttle body and arranged above the plane of entry of 70 the threading passage 6 into the eye 4 and clenched at its free end to lock the guard in place. The opposite end of said shank is bent into a loop 14 crossing itself below the level of said shank but leaving a space 75 between its overlapped portions and extending at 15 on the side of the threading slot opposite to the direction of its original deflection from said transverse shank. The spiral thus formed substantially conforms 80 to the contour of the delivery end of the eye and comprises the downwardly bent loop 14¹ which extends at a slight slope across the plane of entry of the threading passage 6 into the eye. This loop follows the outer 85 wall of the threading eye and as it approaches its downward bend 14¹ is depressed to provide a portion 15 lying slightly below the plane of entry of the threading slot 6. This portion 15 crosses the portion 14 below 90 the level of said transverse shank but leaves a space between its overlap sufficiently large to permit the entrance of the thread from the slot 6. Near this overlap the portion 15 is deflected upwardly to provide a portion 95 15¹ overlying the plane of entry of the threading slot 6 and disposed at an acute angle thereto so as to deflect the thread downwardly and into the confines of the loops 14 and 12. This portion 15¹ terminates on the side of the threading slot 6 opposite to the direction of its original deflection from the transverse shank 13.

On the part 15¹ is formed an inwardly bent pin 16 which is driven into the wood 105 of the shuttle on the upper side of the slot 6 to hold the guard in place. It will thus be observed that the portion 15¹ deflects the thread from the passage 6 into the space left between the overlap of the looped parts 110 14¹ and 15 and thus over the transverse bar 13, from which it feeds in a direction trans-

versely of the shuttle. Any tendency of the thread to run back into the slot 6 is met and prevented by the vertically disposed loop 14¹. Any tendency of the thread to escape by an upward movement is met by the relatively horizontal portion 15 of the guard which portion lies slightly below the plane of entry of the threading slot 6 but in substantially parallelism with said slot. 5
10 The thread is therefore held against escape by any path other than its true path of delivery and feeds from the eye in a uniform even manner.

It will be apparent to any one skilled in 15 the art and familiar with the dethreading tendency due to the writhing and twisting action of the thread during the run of the shuttle, that our improved threading guard will effectively prevent this escape of the 20 thread. It will also be apparent that our construction does away with the usual bushing while at the same time is capable of application to any shuttle of the ordinary type in general use.

25 Various modifications in the bending of the guard, in the material and construction thereof, in the exact disposal of the same, and generally in the details of form and arrangement may obviously be made all without departing from the spirit of our invention if within the limits of the appended 30 claims.

What we, therefore, claim and desire to 35 secure by Letters Patent is:

1. In combination with a shuttle having a delivery eye and a threading passage lead-

ing thereto, a thread guard arranged in said eye and comprising a transverse bar disposed therein above the plane of entry of the threading passage into the eye and having its outer end bent into a loop crossing itself below the level of said transverse bar but leaving a space between its overlap opposite the plane of entry of the threading passage and terminating on the side of the 40 thread slot opposite to the direction of its original deflection from said transverse bar. 45

2. In combination with a shuttle having a delivery eye and a threading passage leading thereto, a thread guard arranged in said 50 eye and comprising a transverse bar set in the shuttle body and disposed therein across the body of the shuttle above the plane of entry of the threading passage into the eye and having its outer end bent into a loop in 55 substantial conformity to the delivery end of said eye and crossing itself below the level of said transverse bar but leaving a space between its overlap opposite the plane of entry of the threading passage and terminating in a point set in the side of the 60 thread slot opposite to the direction of its original deflection from said transverse bar and over the plane of entry of the threading passage into the eye. 65

In testimony whereof we affix our signatures in presence of two witnesses.

JEAN B. DAUDELIN.
EUSEBE H. DAUDELIN.
